(57) **CLAIM**

The ornamental design of a direct drive bicycle trainer, as shown and described.

DESCRIPTION

FIG. 1 is an isometric view of a direct drive bicycle trainer, shown in use, in a first configuration wherein a pair of support legs of the trainer are in an extended position; FIG. 2 is a rear end elevation view thereof; FIG. 3 is a front end elevation view thereof; FIG. 4 is a first side elevation view thereof; FIG. 5 is a second side elevation view thereof; FIG. 6 is a top plan view thereof; FIG. 7 is a bottom plan view thereof; FIG. 8 is an isometric view thereof, illustrating the direct drive bicycle trainer in a second configuration wherein the pair of support legs of the trainer are in a retracted position; FIG. 9 is a rear end elevation view thereof; FIG. 10 is a front end elevation view thereof; FIG. 11 is a first side elevation view thereof; FIG. 12 is a second side elevation view thereof; FIG. 13 is a top plan view thereof; and, FIG. 14 is a bottom plan view thereof. The broken line showing of portions of the direct drive bicycle trainer and bicycle, shown in FIG. 1, depicts environment and forms no part of the claim.
